UNITED STATES PATENT OFFICE.

CHARLES H. ROLLINS, OF WATERTOWN, MASSACHUSETTS, ASSIGNOR OF ONE-HALF TO EDGAR W. ANTHONY, OF BROOKLINE, MASSACHUSETTS.

WATER-CLOSET.

No. 887,660.

Specification of Letters Patent.

Patented May 19, 1908.

Application filed August 15, 1893. Serial No. 169,567.

To all whom it may concern:

Be it known that I, CHARLES H. ROLLINS, of Watertown, in the county of Middlesex and State of Massachusetts, have invented a new and useful Improvement in Water-Closets, of which the following is a specification.

It has been customary in ventilated closets to employ two separate pipes or conduits, one leading from the flushing tank to the closet to supply water thereto, and the other leading from the vent to the usual stack to carry away the air from the bowl. In house constructions these pipes are usually visible and are exposed to the corroding effect of the atmosphere.

The object of the present invention is to reduce the visual number of pipes or conduits by concealing one within the other whereby the closet as a whole presents a neater appearance and has a reduced exposed area of metallic surface. This entails a change in the closet structure as well as a change in the tank structure as will be explained in the accompanying specification.

In accomplishing the object thus referred to, it has likewise been my purpose to provide improvements for preventing upon the surface of the exposed pipe the condensation of moisture. Much trouble and inconvenience is caused by the atmospheric moisture condensing upon the pipe containing the column of flushing water in siphonic closets, the condensed moisture frequently dripping from the pipes onto the floor in such quantities as to seriously injure the polished floor and sometimes causing a stain on the ceiling below. In the present instance, I arrange the flushing pipe within the vent pipe, so that there is between the flushing pipe and the atmosphere an annular column of air contained within the vent pipe which serves as a non-conductor to prevent the vent-pipe from becoming so chilled as to cause the condensation of atmospheric moisture thereon.

Referring to the accompanying drawings:— Figure 1 represents a closet in rear elevation, a tank and the conduit or pipes leading therefrom all in section. Fig. 2 represents a side elevation of the same with the bowl in section. Fig. 3 represents an enlarged section on the line 3—3 of Fig. 1.

The closet is illustrated in the form of a siphon jet closet but it will be understood at the outset that the invention is not limited

to any particular type or style of closet, or to any particular form of flushing apparatus in the tank, its main essential feature consisting in the arrangement of the conduits whereby one is concealed within the other, although it will be also understood that other parts of the invention reside in features of construction and arrangement of parts as pointed out in the appended claims.

The bowl is indicated on the drawing at A, the tank at B and the flushing apparatus at C. The closet has the bowl a and the siphon outlet consisting of the ascending limb a¹ and descending limb a². It is further provided with the flushing rim a³ and the jet duct a⁴ both of which communicate with the inlet chamber a⁵ as shown in Fig. 2. The rear portion of the closet is provided with a vertical annulus or annular flange a⁶ with an upwardly converging interior wall a⁷ for a purpose to be described. This annular flange forms a chamber a⁸ with which communicate the ventilating ducts a⁹ leading from one or both sides of the bowl a as indicated in Fig. 2.

In the initial construction of the closet the chamber a⁸ communicates with the chamber a⁵ by a port or opening in the inner walls of which converge upwardly as indicated at a¹⁰. The inlet or flushing pipe communicates directly with the chamber a⁵ and passes through the chamber a⁸ so that water is never introduced into the last mentioned chamber, which is used solely for the passage of air from the ducts a⁹ to the ventilating conduit. The inlet or flushing pipe is indicated at d and the ventilating conduit at e, the former being relatively small in diameter and the other relatively larger so as to receive the flushing pipe therein as shown in Fig. 3. The upper end of the pipe d communicates with the flushing apparatus C the construction of which is immaterial since the details thereof form no part of the present invention save as hereinafter explained. The pipe e extends upwardly through the bottom of the tank through collars, glands or packing rings f and is connected to an angular casing e' from which a conduit e² extends to the stack, not shown. The conduit e² is provided with an offset downwardly extending portion e³ which is open at its lower end near the bottom of the tank. The pipe d extends upwardly through the casing e' and is provided with the valve d'. It is also provided

with a lateral branch d^2 which extends upwardly and is topped by an air dome d^3 . The pipe e is connected to the annulus a^6 by a suitable coupling device which may be constructed as follows:—An externally threaded sleeve g fits closely but slidingly around the lower end of the pipe d and has screwed upon its upper end a collar g' with an inwardly projecting flange g^2 . Between the flange 10 and the end of the sleeve there is a rubber ring g^3 which when compressed forms a tight joint between the pipe e and the sleeve g . The lower end of the sleeve is expanded as shown and between it and the inner wall of 15 the annulus or annular flange a^6 , is a rubber packing h which is bent outwardly so as to rest upon the top of the annular flange. A collar h' is threaded upon the sleeve and when screwed home draws the sleeve g upwardly so as to form a tight joint between it and the annular flange a^6 . A washer h^2 may 20 be interposed between the collar h' and the gasket h as illustrated. The pipe d is connected or coupled to the chamber a^5 by a 25 coupling similar to, only smaller in size than that just described, and as it differs in no essential respects therefrom it need not be explained in detail any more than to say that k is the sleeve, k' k^2 the collars and k^3 k^4 the 30 rubber gaskets or packings. From this description it will be observed that the only visible connection between the closet and the tank and the stack, is the pipe e and at the same time the nature of the couplings is such 35 as to permit of more or less adjustment of the closet bowl with relation to the tank and the apparatus therein contained. The annular space between the pipe d and the pipe e is of course made sufficient to carry away the 40 air from the bowl.

The downwardly extending portion e^3 of the conduit in the tank affords an overflow for the water in the tank, and the over-flowing water passes down through the ventilating pipe e and through the ducts a^9 into the bowl. By virtue of this construction, the 45 fact that water is wasting, is quickly observed, so that the ball-cock mechanism may be repaired. It is customary in siphon jet 50 closets for the wasting water to pass unobserved into the bowl through the jet duct, so that the present arrangement has advantages.

Having thus explained the nature of the invention, and described a way of constructing and using the same, although without attempting to set forth all of the forms in which it may be made, or all of the modes of its use, I declare that what I claim is:—

1. The combination with a water-closet 60 and a tank, of a vent pipe or conduit leading from the closet through the tank, and a flushing pipe connecting the tank with the closet and being contained within the vent-pipe or conduit from the closet to the tank, substantially as described.

2. The combination with a water-closet and a tank, of a metallic vent-pipe or conduit leading from the closet to the tank and having a branch opening into said tank for the overflow of water from said tank into the bowl through said vent pipe or conduit and a metallic flushing pipe connecting the tank with the closet and arranged within said vent pipe from the tank to the closet.

3. The combination with a tank, and a water-closet having a ventilating chamber and an inlet chamber, one superimposed directly above the other, of a metallic ventilating conduit communicating directly with the flushing chamber and passing through the tank to the atmosphere, and a metallic flushing pipe communicating with the inner chamber and with the tank, said ventilating conduit completely inclosing and concealing said inlet pipe from the closet to the tank, substantially as described.

4. The combination with a water-closet having a ventilating chamber communicating with the bowl and an inlet chamber arranged below the ventilating chamber and communicating with the flushing rim, a flushing-pipe passing through the ventilating chamber, a slip coupling connecting said flushing pipe to the walls of said inlet chamber, a ventilating conduit inclosing and concealing the flushing pipe, and a slip-coupling connecting the ventilating pipe to the walls of the said ventilating chamber.

5. The combination with a water-closet having one or more ventilating ducts, and a tank, of a ventilating conduit leading from the closet and passing through the tank, said ventilating conduit having a branch opening into the said tank for the overflow of water from the tank into the bowl through said conduit, a flushing pipe extending from the closet to the tank within the ventilating conduit and emerging therethrough in the tank, and valve mechanism connected to the flushing pipe and arranged in the tank substantially as described.

6. The combination with a water-closet bowl having a ventilating chamber communicating with the bowl and an inlet chamber directly below the ventilating chamber and communicating with the flushing rim, the walls of said chambers being inwardly beveled, a flushing pipe, a ventilating pipe inclosing the flushing pipe, a sleeve having an expanded lower end clamped to the walls of each of said chambers, and slip-joints between said sleeves and said pipes respectively, substantially as described.

In testimony whereof I have affixed my signature, in presence of two witnesses.

CHARLES H. ROLLINS.
